UNITED STATES PATENT OFFICE

2,508,869

SNUBBED TRUCK BOLSTER

James A. Shafer, East Cleveland, Ohio, assignor
to National Malleable and Steel Castings Company, Cleveland, Ohio, a corporation of Ohio

Application May 15, 1946, Serial No. 669,962

10 Claims. (Cl. 105—197)

1 The invention relates to trucks for railway cars, and more particularly to side frame and bolster construction.

It is an object of my invention to provide a side frame and bolster construction which will accommodate, within the space limitations and strength requirements of standard car construction, an increased number of long-travel coil springs, i. e. springs of greater free height than hitherto has been accepted as standard.

A further object is to provide a construction of the class described in which friction damping mechanism of the improved type disclosed in my copending application, Serial No. 642,793, filed January 23, 1946, or other friction damping mechanism, can be utilized in conjunction with springs of increased free height, and which also will accommodate as many as three sets of such springs within the width of the standard side frame bolster opening, or "window," and as many as five sets of springs in all.

During the past few years the trend in freight car truck design has been to produce a truck that would ride safely at speeds up to 100 miles an hour and which would produce as smooth a ride as possible at that speed. This trend has been focused on the development of long-travel springs, and more particularly in the direction of combining such springs with reliable friction means to control the recoil of the springs.

The total travel of freight car truck coil springs of specifications heretofore accepted as standard is $1\frac{1}{8}$ inch. This represents the difference between the free height and solid height of the springs. Increased spring travel has been obtained by increasing the free height and decreasing the wire diameter to keep the working stress within safe limits while maintaining the solid height of the springs unchanged. Such a spring of standard solid height and having a travel free to solid of $3\frac{1}{8}$ inches has been produced by the use of special oval section wire. Because of the extremely long travel of this spring and of the necessity for limiting the outside diameter to $5\frac{1}{2}$ inches, its capacity is considerably below that of conventional springs. In view of this decreased capacity, a nest of five sets of springs per side frame is required to provide sufficient load carrying capacity for the conventional 50 ton capacity freight car as opposed to the usual four unit standard spring nest. A considerable problem is presented in accommodating five spring units of increased height within the space limitations and strength requirements of standard car construction. This is particularly true where

2 friction damping mechanism is to be utilized in conjunction with such springs of increased height. It has been a particular object of my invention to provide a side frame and bolster construction which will answer this problem while conforming to the many limitations imposed by existing standards of construction.

Other objects and advantages of my invention will appear as the description proceeds.

10 In the drawings:

Fig. 1 is a plan view of a car truck comprising a bolster and side frames embodying the invention, and Fig. 2 is a side elevational view of the same.

15 Fig. 3 is an enlarged cross-sectional view taken as indicated at 3—3 in Fig. 1, with the bolster, the bolster trunnion and one of the friction shoes shown in elevation.

Fig. 4 is an enlarged cross-sectional view taken **20** as indicated at 4—4 in Fig. 1.

Fig. 5 is an enlarged detail sectional view taken as indicated at 5—5 in Fig. 1, except that one of the bolster trunnions is shown in elevation.

25 Fig. 6 is a detail view taken as indicated at 6—6 in Fig. 3 showing the friction shoes in plan.

Figs. 7 and 8 are detail perspective views of one of the friction shoes and sleeve segments respectively.

30 Referring to the drawings, the side frame 10 is formed with a tension member 11, a compression member 12, and connecting columns 13 defining a bolster opening 14. The central portion 15 of the tension member comprises a bottom wall 16, side walls 17 (Fig. 4), and a top wall or shelf 18 forming a spring seat on the side frame adjacent the top of the tension member at the lower side of the bolster opening.

Openings 19 (Fig. 5) are formed in the top of **40** the tension member at each side of the spring seat 18 to receive spring units 20, 21, seating in the lower part of the tension member.

Flanges 22 extend downwardly from the spring seat 18 adjacent the openings 19 in the top of the **45** tension member. In my preferred construction these are annular or tubular flanges extending downwardly from the periphery of the spring openings and they merge with the side walls 17 of the tension member 11.

Flanges 23 extend upwardly from the periphery of the aforesaid openings 19, leaving a space *a* between them opposite the spring seat 18 for adjacent arrangement of upper and lower spring units 20, 21 overlapping at the spring seat, and **50** to provide for insertion of the lower springs in

3

a manner to be described. Thus we have flanges extending upwardly and downwardly from the periphery of the spring openings in the tension member, the upwardly extending flanges leaving a space a opposite the spring seat (Fig. 6) and the downwardly extending flanges extending underneath the spring seat (Fig. 5). The upwardly extending flanges 23 are in effect continuations of the downwardly extending flanges 22 except where they are spaced apart to provide the opening a to which reference has been made (see Figs. 3 and 5). Flanges 23 preferably are formed as integral extensions of the walls of the columns 13 at the sides of the bolster openings as clearly shown in Fig. 6, and at their upper ends are reinforced as at 24 by an outwardly projecting rib or flange and further reinforced by webs 25 (Fig. 3).

Friction sleeves comprising sleeve segments 26 are supported in the openings 19. One of these sleeve segments is shown in Fig. 8. It is formed with an outwardly extending flange 27 at its upper end which is arranged to extend over the top of the upwardly extending flange 23 to prevent the sleeve segment from moving vertically downward. At its lower end each sleeve segment is provided with an outwardly extending flange 28 which, in the preferred construction illustrated, is of arcuate form so as to fit within one of the openings 29 in the side walls 17 of the tension member of the side frame. Thus the arcuate flange 28 extends below the downwardly extending flange 22 where the latter merges with the side wall 17 of the frame (Figs. 2 and 3). The construction I have described provides interlocking engagement between the segments of the friction sleeve and the flanges of the side frame to prevent upward and downward movement of the segments.

The spring seat 18 has lateral extensions 30 reinforced by webs 31 (Fig. 4) to support additional spring units 20, 21 providing three spring units seating adjacent the top of the tension member in a line transversely of the side frame. The spring units are positioned by suitable centering means such as provided by the upwardly extending lugs 32. Centering means for the lower spring units are provided by shoulders 33 and by a lug or flange 34 extending upwardly from the lower part of the tension member. The end 35 of truck bolster 36 is received in opening 14 of the side frame 10. Downwardly extending flanges 37 of the end of the bolster provide recesses for the three upper spring units as clearly shown in Fig. 4. On the under surface of bolster end 35 are downwardly extending trunnions 38, each having a pair of plane wedging surfaces 39, 40. The wedge shaped portions of the trunnions extend downwardly into wedging engagement with friction shoes 41 which rest on top of the lower spring units 20, 21 and are partially encased by sleeve segments 26. Laterally extending lugs 42 on the friction shoes prevent rotation of the shoes by engagement with ends 43 (Fig. 6) of sleeve segments 26. Each of the shoes 41 has a curved surface 44 for engagement with the inner surface of the adjacent sleeve segment 26. It will be observed that the radius of curvature of the cylindrical friction shoe surfaces is slightly smaller than the radius of curvature of the inner cylindrical surfaces of the sleeve segments 26. This is for the purpose of having the initial wear occur at the central portion of the sleeve segments and shoe along the line of action of the thrust from the wedge surfaces,

thus eliminating any bending stresses in the shoes or sleeve segments, and also causing the shoes to wear until their surfaces substantially conform to the cylindrical surfaces of the sleeve segments. Also, the outer surfaces of segments 26 have a radius of curvature which is slightly smaller than the inner surfaces of flanges 22, 23. Each of the bolster trunnions 38 is recessed or flattened at 45 to provide laterally extending downwardly projecting lugs 46 for engagement with the lugs 42 of the friction shoes (Fig. 3) to limit movement of the bolster transversely of the side frame. This arrangement maintains adequate thrust surfaces between the truck bolster and the friction shoes associated with the side frame without interfering in any way with the wedging contact between the bolster and friction shoes.

Upon downward movement of the bolster relative to the side frame, friction shoes 41 are forced outwardly against friction sleeve segments 26 by wedge surfaces 39, 40 on bolster trunnions 38. The absorption of the energy of the movement quickly brings to a stop any oscillations of the springs, thus preventing subsequent shocks from building up the amplitude of spring oscillations to a point where damage might be done to the car lading. The springs are prevented from being damaged in the event of an unusually heavy blow by the engagement of the under surface 47 of the bolster with the top surface of sleeve segments 26.

An important feature of my side frame construction is the provision of the opening a between the ends of the upwardly extending flanges 23. This arrangement not only permits the springs to be arranged closer together, as will be apparent from consideration of Fig. 5, but also makes it possible to insert springs of increased free height into the side frame. With reference to the first of these advantages, it is to be observed that the width W of the window opening in the side frame is restricted by the necessary standard location of the brake hanger brackets, the centers of which must be spaced $10\frac{1}{2}$ inches on either side of the vertical centerline of the frame. However it will be observed that my construction, in which the spring seat adjacent the top of the tension member is provided with flanges extending upwardly and downwardly from the periphery of the spring openings, and in which the upwardly extending flanges are spaced as aforesaid, permits three springs to be arranged on the longitudinal centerline of the frame within the width W of the window opening for the bolster. This arrangement further provides guiding means for the spring units which are adjacent the columns 13 of the frame, this guiding means comprising flanges 22 which extend entirely around the spring units and underneath the spring seat for the center spring unit to reinforce this seat. With reference to the second advantage mentioned above, it will be observed that the free height of the spring units 20, 21 is greater than the distance between the under side of the compression member 12 and the top of the upwardly extending flanges 23. However the opening a between the ends of these flanges makes it possible to insert the lower spring units 20, 21 by tilting them into place.

The importance of the features which I have described from the standpoint of making it possible to utilize an increased number of long-travel coil springs in conjunction with a side frame and bolster construction which conforms to the space

limitations and strength requirements of standard car construction, will be readily appreciated by car truck designers. In this connection it may be noted here that the over-all height A of the side frame is definitely fixed and limited by rail clearance and by car body clearance. The thickness B of the compression member 12 must be sufficient to meet strength requirements, and the distance C from the top of the bolster to the under side of the compression member is determined by the amount the bolster must be lifted in order to assemble and disassemble the truck. Consequently the total height available for reception of the bolster, springs and friction mechanism is quite definitely restricted. That my construction meets these space limitations and strength requirements, while permitting the use of a greater number of long-travel spring units in combination with friction damping mechanism, will be apparent from the description which has preceded. An additional characteristic of the construction described is the provision, in a side frame comprising a box shaped tension member, of three springs seating adjacent the top of the tension member in a line transversely of the frame, with openings in the top of the tension member at each side of this line of springs and opposite the center one of the three springs, and springs extending through these openings and seating in the lower part of the tension member to provide five springs, three of which are arranged in vertically overlapping relation to the other two.

An additional advantage of the flange construction 22, 23 is that besides guiding the lower spring units and reinforcing the spring seat 18, it supports the friction mechanism.

In assembling my truck, the sleeve segments 26 are first put in place, their upper flanges 27 resting on the upper edges of the walls or flanges 23 and their lower flanges 28 hooking under the flanges 22 which at that point are defined by the round openings 29 through the side frame. The two lower spring units 20, 21 are then inserted through the openings 19 between the sleeve segments 26. During insertion of these spring units they are tipped so that their upper ends incline toward the center of the window opening 14. As they are started down through the openings 19, they are straightened up to the vertical and come to rest in the positions shown in Fig. 5. The friction shoes 41 are then dropped into place on top of the springs. Next the bolster 36 with the upper three spring units 20, 21 temporarily suspended therefrom, is inserted into the window opening 14 of the side frame (Fig. 4) and lowered until the bolster trunnions 38 come to rest on the friction shoes 41 as shown in Fig. 3. In the assembly each part is accurately positioned and locked in place by the part previously assembled, and after a unit has been inserted no further positioning of that unit is needed to enable the next unit to be properly positioned.

The cooperation between the trunnions 38 of the bolster and the other parts of the friction mechanism in resisting thrust endwise of the bolster, i. e. laterally of the track, and in producing a squaring action on the side frames after rounding a section of curved track, is similar to that described in my copending application Serial No. 642,793 aforesaid. When one of the side frames of the car truck tends to run ahead of the other, such as the case would be in rounding a curve, one trunnion tends to slide up the wedge surfaces of one of the friction shoes, while the

other trunnion tends to slide up the wedge surfaces of the shoe diagonally opposite the aforesaid shoe, causing a vertical displacement of the bolster and the car. As the trunnions rise on the one set of diagonally opposed shoes, the other diagonally opposed set is left free. Thus, when the force tending to keep the truck out of square is diminished, the weight of the car and bolster acting on the diagonally opposed wedging surfaces produces a couple which acts to bring the truck back into its proper alignment. The sliding of the trunnion up the wedge surfaces of the friction shoes is limited by the thrust engagement between the lugs 42 of the shoes and lugs 46 of the trunnions. This limits the amount the truck can get out of square. The vertical interlock between the lugs of the trunnions and friction shoes remains substantially the same regardless of the angle of the wedge surfaces of the bolster and shoes.

The terms and expressions which I have employed are used in a descriptive and not a limiting sense, and I have no intention of excluding such equivalents of the invention described, or of portions thereof, as fall within the purview of the claims.

I claim:

1. A side frame for car trucks, said frame comprising a box-shaped tension member, three springs seating adjacent the top of the tension member in a line transversely of said frame, openings in the top of the tension member at each side of said line and opposite the center one of the three springs, springs extending through said openings and seating in the lower part of the tension member to provide five springs three of which are arranged in vertically overlapping relation to the other two, flanges extending upwardly and downwardly from the tension member around said openings in the tension member, and friction sleeves supported by said flanges and having outwardly extending portions engaging the upper and lower ends of said flanges.

2. In a car truck comprising a bolster and side frames, a side frame having tension and compression members and columns therebetween defining a bolster opening, a spring seat on the side frame adjacent the top of the tension member at the lower side of the bolster opening, an opening in the top of the tension member at one side of said spring seat to receive a spring seating in the lower part of the tension member, and flanges extending upwardly from the periphery of said opening leaving a space between them opposite said spring seat for adjacent arrangement of springs overlapping vertically at said spring seat.

3. In a car truck comprising a bolster and side frames, a side frame having tension and compression members and columns therebetween defining a bolster opening, a spring seat on the side frame adjacent the top of the tension member at the lower side of the bolster opening, an opening in the top of the tension member at one side of said spring seat to receive a spring seating in the lower part of the tension member, and flanges extending upwardly and downwardly from the periphery of said opening, the upwardly extending flanges leaving a space opposite said spring seat and the downwardly extending flange extending underneath said spring seat.

4. In a car truck comprising a bolster and side frames, a side frame having tension and compression members and columns therebetween

defining a bolster opening, a spring seat on the side frame adjacent the top of the tension member at the lower side of the bolster opening, an opening in the top of the tension member at one side of said spring seat, flanges extending upwardly and downwardly from the tension member around said opening in the tension member, a friction sleeve supported by said flanges and having outwardly extending portions engaging the upper and lower ends of said flanges, a spring arranged in line with the sleeve and supported in the lower part of the tension member and extending through said opening, friction shoes arranged for frictional engagement with the sleeve above said opening and for movement against the resistance of said spring, each of said shoes having a wedge surface, and the bolster having a wedge surface on its underside for engagement with the wedge surface of each shoe.

5. In a car truck comprising a bolster and side frames, a side frame having tension and compression members and columns therebetween defining a bolster opening, a spring seat on the side frame adjacent the top of the tension member at the lower side of the bolster opening, an opening in the top of the tension member at one side of said spring seat to receive a spring seating in the lower part of the tension member, flanges extending upwardly and downwardly from the periphery of said opening, the upwardly extending flanges leaving a space opposite said spring seat and the downwardly extending flange extending underneath said spring seat, and friction sleeve segments supported by said upwardly and downwardly extending flanges.

6. In a car truck comprising a bolster and side frames, a side frame having tension and compression members and columns therebetween defining a bolster opening, a spring seat on the side frame adjacent the top of the tension member at the lower side of the bolster opening, an opening in the top of the tension member at one side of said spring seat to receive a spring seating in the lower part of the tension member, flanges extending upwardly and downwardly from the periphery of said opening, the upwardly extending flanges leaving a space opposite said spring seat and the downwardly extending flange extending underneath said spring seat, and friction sleeve segments supported by said upwardly and downwardly extending flanges, said segments having interlocking engagement with said flanges to prevent upward and downward movement of the segments.

7. A side frame for car trucks, comprising tension and compression members and columns therebetween defining a bolster opening, a spring seat formed adjacent the top of the tension member at the lower side of the bolster opening, 60

an opening in the top of the tension member at one side of said spring seat, flanges extending upwardly and downwardly from the periphery of said opening, and friction sleeve segments supported by said upwardly and downwardly extending flanges.

8. A side frame for car trucks, comprising tension and compression members and columns therebetween defining a bolster opening, a spring seat formed adjacent the top of the tension member at the lower side of the bolster opening, an opening in the top of the tension member at one side of said spring seat, flanges extending upwardly and downwardly from the periphery of said opening, and friction sleeve segments supported by said upwardly and downwardly extending flanges, said segments having interlocking engagement with said flanges to prevent upward and downward movement of the segments.

9. A side frame for car trucks, comprising tension and compression members and columns therebetween defining a bolster opening, a spring seat formed adjacent the top of the tension member at the lower side of the bolster opening, openings in the top of the tension member at each side of said spring seat and between it and said columns to receive springs seating in the lower part of the tension member, flanges extending upwardly and downwardly from the periphery of said openings, and friction sleeve segments supported by said upwardly and downwardly extending flanges.

10. A side frame for car trucks, comprising tension and compression members and columns therebetween defining a bolster opening, a spring seat formed adjacent the top of the tension member at the lower side of the bolster opening, openings in the top of the tension member at each side of the spring seat and between it and said columns, springs extending through said openings and seating in the lower part of the tension member, a spring seating on said spring seat between the first-named springs, and flanges extending upwardly from the periphery of each of said openings leaving a space between them opposite said spring seat for adjacent arrangement of springs overlapping vertically at said spring seat.
